(57) CLAIM

The ornamental design for hooded apparel, substantially as shown and described.

DESCRIPTION

FIG. 1 is a perspective view of hooded apparel showing my new design;

FIG. 2 is a front elevational view of the hooded apparel of FIG. 1.

FIG. 3 is a rear elevational view of the hooded apparel of FIG. 1.

FIG. 4 is a left elevational view of the hooded apparel of FIG. 1.

FIG. 5 is a right elevational view of the hooded apparel of FIG. 1.

FIG. 6 is a top plan view of the hooded apparel of FIG. 1; and, FIG. 7 is a bottom plan view of the hooded apparel of FIG. 1. The broken lines are included for illustrative purposes only and form no part of the claimed design.
